UNITED STATES PATENT OFFICE.

JOHN R. REFLOGLE, OF DETROIT, MICHIGAN, ASSIGNOR, BY MESNE ASSIGNMENTS, TO
ELECTRIC REFRIGERATION CORPORATION, OF DETROIT, MICHIGAN, A CORPORA-
TION OF MICHIGAN.

DAMPER FOR VENTILATOR OPENINGS.

Application filed March 14, 1921, Serial No. 452,397. Renewed October 17, 1927.

This invention relates to thermally controlled devices for ventilator openings for cooling chambers and more particularly to refrigerators having valves or dampers and 5 operating means therefor for controlling the circulation of air through the food compartment and refrigerating chamber.

One of the objects of the invention is to provide means for automatically regulating 10 the amount of a fluid flowing through an opening such as a current of air flowing through a ventilating opening in a refrigerator or other cooling device.

Another object of the invention is to 15 maintain a compartment that communicates with a cooling chamber at a uniform temperature.

Another object of the invention is to provide a refrigerator having thermally controlled means for maintaining the food compartment of a refrigerator at a uniform temperature above that within the brine tank 20 chamber.

Still another object of the invention is the 25 construction of a thermally operated valve or damper that comprises a separate independent self-contained unit that is compact and simple in construction, efficient in operation, that is composed of few moving parts, 30 and is not likely to get out of order.

While my device is primarily designed to be employed in connection with mechanically operated refrigerators, still it is understood that it may be employed in connection with refrigerators of other forms such as those employing ice as the cooling 35 agent.

Other and further objects and advantages 40 of the invention will appear from the following description and drawing in which;

Fig. 1 is a front view of a refrigerator with parts broken away and showing the device in position therein;

Fig. 2 is an enlarged vertical section of the 45 valve or damper;

Fig. 3 is a top plan view of the device shown in Fig. 2 with the top portion of the casing removed, parts being in section and parts broken away.

On the drawings, the numeral 1 indicates a 50 refrigerator having the food compartments 2 and 3 and the refrigerating chamber 4. The partition 5 separates the food compartment

2 from the refrigerating chamber 4 at its upper end and separates the food compartments 2 and 3 at its lower end. A compartment in the lower part of the refrigerator closed by the removable cover 10 may contain the usual motor, compressor, condenser and attendant mechanism, as is well understood.

The partition 5 has at its upper end the opening 6 and at the lower the opening 7 for the passage of air therethrough. The bottom wall 9 of the refrigerating chamber 4 is provided with an opening 8 through which the cooler air from the chamber 4 may pass into the compartment 3, and from thence into the compartment 2 and becoming heated rises and passes through the opening 6 into the refrigerating chamber 4.

The opening 8 is shown as being circular, but it is understood that it may be of any convenient shape or size. It may be, and preferably is, provided with the lining member 11 which may be secured therein by any suitable means. This means may consist in providing the lining 14 with a flange 13 extending around the opening 8, over which the return bend 12 of the lining member 11 is adapted to engage and be secured thereto by any suitable means. The lower lining 19 may also be provided with an upwardly extending flange 13' which engages, and makes a close fit with, the exterior surface of the 55 lining member 11.

A valve or damper mechanism is employed to regulate the flow of air through the opening 8. This mechanism is operated by means controlled by the temperature within the food compartment and is made in any convenient manner and secured by suitable means within the opening 8. As shown, this mechanism is a unitary structure and consists of an attaching or supporting ring 15, 60 a casing or housing 31, a protecting or housing member 22, valve or closure 40, 41 and valve control and operating mechanism.

The attaching or supporting ring 15 constitutes an attaching flange for supporting 100 the valve mechanism within the opening 8. This ring 15 may be of any suitable size but preferably its internal diameter is substantially the same as that of the lining member 11. This ring is provided with inwardly 105 extending projections 16' to which are se-

cured the laterally bent lower ends of brackets 16 which are attached to the housing 31 for supporting the same from said ring.

The protecting or housing member 22 which may be of substantially the same diameter as the lining member 11, is secured to the lower side of the ring 15 by means of the bolts 17 which engage openings through the brackets 16, the projections 16' and 30 10 on the ring 15, and the inwardly extending lugs 17' carried by the upper end of the member 22, thus securing the parts together to form a unitary structure. The member 22 and the housing 31 together form a conducting passage or casing through which the air within the refrigerator is adapted to circulate.

In applying the unitary valve or damper mechanism to the opening 8, the casing or housing 31 is slid up within the said opening until the upper side of the ring 15 comes in contact with the lower lining 19. The ring or flange 15 is secured by any suitable means to the bottom wall 9. One form of attaching means is shown in Figs. 2 and 3. A semi-circular plate 20 having the studs 21 rigidly attached thereto, is placed about the opening 8 with the studs extending through the lower lining 19. The ring 15 is secured 25 to these studs by the usual nuts, as clearly shown in Fig. 2. By this arrangement of attaching means, the bolts or studs 21 are prevented from turning while the nuts are being applied, and, moreover, all danger of 30 injury to the lower lining is eliminated.

The member 22 may be provided with the laterally extending supporting members 23 at its lower end. These members, however, may be omitted, and, in fact, are omitted in 40 the actual construction of the device. These members have their outer ends bent upwardly and spaced from the member 22 to form seats for supporting the enlarged tube or annular thermostat bulb 24. A spider 25 45 is secured beneath the member 22 and has the arms 26 which extend laterally beyond the member 22 and have their outer ends bent upwardly in spaced relation to the casing to form guards or supports for the thermostatic bulb 24. The member 22 protects 50 the thermostat bulb from coming in direct contact with the cooler air from the chamber as it flows through the opening.

A housing 27 has the top 28 thereof provided with attaching ears 29 which are secured to supporting lugs 30 on the supporting ring 15. The top 28 of the housing is slotted as at 32' and has the ears 33 secured thereto. Pivoted between the ears 33 is the 60 lever 34 which has the weights 35 and 35' adjustably connected to its outer end.

A plug 36 is secured to the lower open end of the housing 27, as by being screwed therein. This plug has an opening 37 through 65 which projects the screw-threaded lower end

38 of a corrugated longitudinally expandible member or bellows 38'. The bellows is secured in position by means of the lock nut 39. A projection on the upper end of the bellows is pivoted to the lever 34 by means of a pin and slot arrangement.

The housing 31 is provided with a closure or valve which in the form shown consists of the two leaves 40 and 41 pivoted to the supporting members 42 which are attached to the supporting ring 15. The leaves may if desired be covered with insulating material and are operated by being connected to the lever 34. Links 43 and 44 are pivoted to the leaves 40 and 41, respectively, of the cover. 75 These links extend laterally and downwardly toward each other and are so bent that their lower ends extend downwardly through a rectangular opening 45 formed in the outer end of the lever 34. A U-shaped member 46 80 has its upper ends pivoted to lugs 46' on the sides of the lever forming the rectangular opening 45, and has its lower end pivoted to the lower ends of the links 43 and 44 at 47.

The thermostat bulb 24 having the charging valve arrangement 48 is adapted to extend about the member 22 and rest in the seat formed by the member 23. Its reduced end 50 extends through a slot 49 in the member 22 and is connected to the lower end of the bellows. The weights 35 and 35' are adjusted along the lever to the point where the device will open the valve or damper at a predetermined temperature. Further adjustment may be accomplished by means of the 90 plugs 36 and the locking nut 39. A charge 95 of fluid that vaporizes at comparatively low temperatures such as sulphur dioxide is placed within the bulb 24. In order to insure a uniform expansion of the fluid within the bulb, a sufficient supply of the liquid is employed so that there will always be some of the liquid in the bulb that is not vaporized. It will be noted that the reduced portion of 100 the thermostat is elevated so that the liquid 105 will remain in the bulb 24.

When the temperature of the air about the bulb rises above a predetermined maximum the liquid within the bulb vaporizes sufficiently to create a sufficient pressure to open 115 the leaves 40 and 41 slightly, and as the temperature of the bulb rises the leaves will open more and more to permit the cooler air to pass through the opening.

It will be thus be observed that owing to 120 the relatively large size of the bulb it readily responds to changes in temperatures within the food compartment with the result that the leaves 40 and 41 are so manipulated that the temperature within the food 125 compartment is kept uniform.

While I have shown and described the device as being employed in a refrigerator it is understood that it is not so limited in its use as it may be employed in any opening 130

through which a fluid is adapted to flow as a result of unequal temperatures on the two sides of the opening. It is also understood that the invention is not limited to the details of construction shown and described, as changes in the form, proportions and details of the construction may be varied within the scope of the appended claims.

I claim:

1. In a unitary device for controlling the circulation of air through an opening, the combination of a tubular casing having open ends and adapted to register with an opening in a wall; a closure for the passage through said casing movably mounted thereon; actuating means for the closure, comprising a device operatively connected to the closure and located within the casing and a thermostat bulb operatively connected to said device disposed and supported on the outer side of the casing and protected thereby from the current of air passing therethrough.
2. In a unitary device for controlling the circulation of air through an opening, the combination of a tubular casing having open ends and adapted to register with an opening in a wall; a closure for the passage through the casing movably mounted thereon; means for actuating the closure comprising an expansible device operatively connected to the closure and a thermostat bulb operatively connected to said expansible device; and means for supporting the said bulb so that it is protected from the current of air passing through the casing.
3. In a unitary device for controlling the circulation of air through an opening, the combination of a tubular casing having open ends and adapted to register with an opening in a wall; a closure for the passage through the casing movably mounted thereon; and means for actuating the closure comprising an expansible device operatively connected to the closure and arranged within the casing and a thermostat bulb disposed and supported on the outer side of the casing and protected thereby from the current of air passing therethrough.
4. In a unitary device for controlling the circulation of air through an opening, the combination of a tubular casing having open ends and adapted to register with an opening in a wall; a closure for the casing passage movably mounted at one end of the casing; and means for actuating the closure comprising an expansible device operatively connected with the closure and disposed within the casing and a thermostat bulb extending around the outer side of the casing near the other end thereof and communicating with the interior of said expansible device.
5. In a thermally controlled valve device, a casing having an opening therethrough for fitting an opening in a support, an enlarged tube about said casing for containing an expansible fluid, said tube terminating in a reduced portion secured to one end of a corrugated longitudinally expansible member, a weighted lever connected to the other end of said member and pivoted closures operated by said lever for closing said opening through said casing, substantially as shown and described.
6. In a ventilator controlling device, a housing, a hinged cover therefor, an expansible member within said housing, means including a lever having an adjustable weight thereon, connecting said closure with said expansible member, and a thermostat about said housing and in communication with said expansible member for controlling the movements of said closure, substantially as shown and described.
7. In a ventilator controlling device, a cylindrical member, an attaching ring secured to one end of said member, a cover for the other end of said member, said cover consisting of a plurality of pivoted leaves, a link pivoted to each leaf for operating the same, a longitudinally expansible member, a lever, a weight adjustably mounted on the free end of said lever, said lever pivoted between its ends to said expansible member, means connecting said lever to said links, a cylindrical member connected to said ring, a spider beneath said last named cylindrical member and having arms extending outward and upward to form seats, a thermostat bulb located without said cylindrical members within said seats and having a reduced portion connected to said expansible member substantially as shown and described.
8. In a refrigerator, a wall having a ventilating opening therethrough, a pivoted cover for closing said opening, mechanism including a lever for operating said cover, a weight adjustably mounted on said lever, an expansible member connected to said lever, and a thermostat bulb conforming to the shape of said opening and arranged about the same on the opposite side of the wall from said cover and connected to said expansible member for controlling the operation of said cover substantially as shown and described.

In testimony whereof I affix my signature.

JOHN R. REPLOGLE.
